UNITED STATES PATENT OFFICE.

OTTO TITUS BLÁTHY, OF BUDAPEST, AUSTRIA-HUNGARY.

CONSTRUCTION OF ELECTRICAL METERS.

SPECIFICATION forming part of Letters Patent No. 794,656, dated July 11, 1905.

Application filed November 10, 1902. Serial No. 130,733.

To all whom it may concern:

Be it known that I, OTTO TITUS BLÁTHY, a subject of the Emperor of Austria-Hungary, residing at Budapest, Austria-Hungary, have 5 invented new and useful Improvements in or Relating to the Construction of Electrical Meters, of which the following is a specification.

My invention relates to an improved construction of electrical meters whereby such apparatuses are greatly simplified, the number of subsidiary parts of which the main parts are composed being greatly reduced, while at the same time a construction of great 15 strength and durability is obtained.

According to my present invention all the parts of the counter apparatus, or a greater or smaller number thereof, are arranged in a row upon bars or bolts which are passed 20 through the base-plate or are otherwise fixed thereto, after which the position of the parts arranged side by side are secured by means of screw-nuts, wedges, or other suitable appliances.

25 For insuring the correct relative position of the several bearing-bolts special tie-pieces may be slid thereon, these being, however, superfluous if the cover of the casing is also threaded on the bearing-bolts.

30 On the accompanying drawings are shown three modifications of an electrical motor-counter according to my said invention.

Figure 1 shows one construction of the improved counter in longitudinal section, the 35 counting mechanism being omitted. Fig. 2 shows a cross-section on line $\alpha\alpha$, Fig. 1, the casing being omitted. Fig. 3 shows a longitudinal section of the second modification, and Fig. 4 a front view of the same, the casing 40 being removed. Figs. 5 and 6 are similar views of a further modification.

As shown in Fig. 1, bearing-bolts 7 are passed through the base-plate 6 of the casing. They may, however, be fixed otherwise there- 45 to. On these bolts are slid electromagnets 1, the bearing-pieces 3 for supporting the armature-spindle, and the braking-magnets 2, suitable annular distance-pieces 8 or equivalent devices being interposed between the several 50 parts, these being then pressed firmly together

by means of screw-nuts 9. On the bolts 7 may also be mounted the cover 5 of the casing, this being secured by means of screw-nuts 10 or by other suitable means.

The counter mechanism is by way of example not shown mounted on the bearing-bolts in the arrangement at Figs. 1 and 2, while in the construction shown at Figs. 3 and 4 the counting mechanism 4 is also carried by the bolts 7'. The bolts 7' are in this construction 60 formed with collars 11, so that the electro- magnet 1 and the bearing-piece 3 are situated between the base-plate 6 and the collar 11, while on the other side of the collar of the upper bolts only the counter mechanism is 65 mounted. The parts are secured in position by means of screw-nuts 10 and 12, screwed on the ends of the bolts 7'. With the construction at Figs. 3 and 4 there is provided, by way of example, only a single braking-mag- 70 net 2', having its one pole above and the other pole below the disk-armature.

As shown at Fig. 3, it is not necessary to mount the cover 5' of the casing upon the bolts 7'. It can be secured in any suitable manner 75 either to the base-plate or to the tie-pieces 13. These tie-pieces serve to secure the bearing- bolts 7' in their relative position, being mounted thereon as shown. They are either of the closed annular form, (indicated at Fig. 4,) so 80 as to connect together the four bolts 7, or they may be formed so as only to tie two of the bolts 7' together, as shown in Fig. 6 at 13'. These tie-pieces may be arranged either in one and the same plane or in different planes. 85

The separate parts, such as the braking- magnets 2, can, if necessary, be arranged in any known manner upon the bolts, such as by being placed between two screw-nuts on the bolts, so as to be adjustable in position, 90 as shown in Fig. 5 at 2''.

In the examples shown on the drawings the several parts are carried by four bearing-bolts; but these can of course be either greater or less in number. Furthermore, other compo- 95 nent parts of the counter apparatus not above referred to, but which are to be found in some of the apparatus of this kind, can also be mounted on the bearing-bolts, while smaller parts or such as cannot be conveniently mount- 100

ed upon the bolts can be otherwise secured, such as to the tie-pieces 13.

The securing of the bearing-bolts to the base-plate and the pressing together or fixing of the component parts that are mounted on the bolts can be effected in various other ways besides those shown.

The construction and action of such counter apparatus is the same as that of electrical motor-counters of known construction and need, therefore, not be further described.

Having now particularly described and ascertained the nature of my said invention and in what manner the same is to be performed, 15 I declare that what I claim is—

1. In an electrometer of the class described, a base-plate, bearing-bolts secured thereto, electromagnets, bearing-pieces and permanent magnets all carried by the same bolts, distance- 20 pieces on the bolts between the aforesaid parts and an armature having its spindle journaled in the bearing-pieces, substantially as described.

2. In an electrometer of the class described, 25 a base-plate, bearing-bolts secured thereto, electromagnets, bearing-pieces and permanent magnets all carried by the same bolts, tying means insuring the relative positions of the bearing-bolts, distance-pieces on the bolts between the aforesaid parts and an armature having its spindle journaled in the bearing-pieces, substantially as described.

3. In an electric meter of the class described, 35 a base-plate, bearing-bolts suitably secured thereto, the different parts of said meter mounted side by side on said bearing-bolts, means to secure said parts in position, the cover of the meter-casing mounted on said bearing-bolts and means to secure it thereon, substantially as and for the purpose specified.

4. In an electric meter of the class described, 45 a base-plate, bearing-bolts suitably secured thereto, the different parts of said meter mounted side by side on said bearing-bolts, distance-pieces interposed between said parts, means to secure said parts in position, the cover of the meter-casing mounted on said bearing-bolts and means to secure it thereon, substantially as and for the purpose specified.

5. In an electric meter of the class described, 50 a base-plate, bearing-bolts suitably secured thereto, the different parts of said meter mounted side by side on said bearing-bolts, means to secure said parts in position, tie- 55 pieces insuring the relative position of said bearing-bolts, the cover of the meter-casing mounted on said bearing-bolts and means to secure it thereon, substantially as and for the purpose specified.

6. In an electric meter of the class described, 60 a base-plate, bearing-bolts suitably secured thereto, the different parts of said meter mounted side by side on said bearing-bolts, distance-pieces interposed between said parts, 65 means to secure said parts in position, tie-

pieces insuring the relative position of said bearing-bolts, the cover of the meter-casing mounted on said bearing-bolts and means to secure it thereon, substantially as and for purpose specified.

70

7. In an electric meter of the class described, a base-plate, bearing-bolts passed through said base-plate, the different parts of said meter mounted side by side on said bearing-bolts, screw-nuts to secure said parts in position, 75 the cover of the meter-casing mounted on said bearing-bolts and screw-nuts to secure it thereon, substantially as and for the purpose specified.

8. In an electric meter of the class described, 80 a base-plate, bearing-bolts passed through said base-plate, the different parts of the meter mounted side by side on said bearing-bolts, distance-pieces interposed between said parts, screw-nuts to secure said parts in position, 85 the cover of the meter-casing mounted on said bearing-bolts and screw-nuts to secure it thereon, substantially as and for the purpose specified.

9. In an electric meter of the class described, 90 a base-plate, bearing-bolts passed through said base-plate, the different parts of the meter mounted side by side on said bearing-bolts, tying means insuring the relative position of said bearing-bolts, screw-nuts to secure said 95 parts in position, the cover of the meter-casing mounted on said bearing-bolts and screw-nuts to secure it thereon, substantially as and for the purpose specified.

10. In an electric meter of the class described, 100 a base-plate, bearing-bolts passed through said base-plate, the different parts of the meter arranged side by side on said bearing-bolts, distance-pieces interposed between said parts, screw-nuts to secure said parts in 105 position, tying means insuring the relative position of said bearing-bolts, the cover of the meter-casing mounted on said bearing-bolts and screw-nuts to secure it thereon, substantially as and for the purpose specified.

110

11. In an electric meter of the class described, 115 a base-plate, bearing-bolts suitably secured thereto, the electromagnets, permanent magnets, the bearing-pieces of the armature-axle being arranged side by side on said bearing-bolts, means to secure said parts in position, substantially as and for the purpose specified.

12. In an electric meter of the class described, 120 a base-plate, bearing-bolts suitably secured thereto, the electromagnets, braking-magnets and the bearing-pieces of the armature-axle being mounted side by side on said bearing-bolts, distance-pieces interposed between said parts, means to secure said parts 125 in position, substantially as and for the purpose specified.

13. In an electric meter of the class described, 130 a base-plate, bearing-bolts suitably secured thereto, the electromagnets, braking-

5 magnets and the bearing-pieces of the armature-axle being mounted side by side on said bearing-bolts, distance-pieces interposed between said parts, tie-pieces to insure the relative position of said bearing-bolts, means to secure the parts arranged on the bearing-bolts, substantially as and for the purpose specified.

10 14. In an electric meter of the class described, a base-plate, bearing-bolts suitably secured thereto, the electromagnets, permanent magnets, the bearing-pieces of the armature-axle and the registering mechanism being arranged side by side on said bearing-bolts, means to secure said parts in position, substantially as and for the purpose specified.

15 15. In an electric meter of the class described, a base-plate, bearing-bolts suitably secured thereto, the electromagnets, braking-magnets, the bearing-pieces of the armature-axle and the registering mechanism being mounted side by side on said bearing-bolts, distance-pieces interposed between said parts, means to secure said parts in position, substantially as and for the purpose specified.

20 16. In an electric meter of the class described, a base-plate, bearing-bolts suitably secured thereto, the electromagnets, braking-magnets, the bearing-pieces of the armature-axle and the registering mechanism being mounted side by side on said bearing-bolts, distance-pieces interposed between said parts, tie-pieces insuring the relative position of said bearing-bolts, means to secure said parts on the bearing-bolts, substantially as and for the purpose specified.

25 17. In an electric meter of the class described, a base-plate, bearing-bolts suitably secured thereto, the electromagnets, braking-magnets, the bearing-pieces of the armature-axle being arranged side by side on said bearing-bolts, means to secure said parts in position, the cover of the meter-casing mounted on said bearing-bolts and means to secure it thereon, substantially as and for the purpose specified.

30 18. In an electric meter of the class described, a base-plate, bearing-bolts suitably secured thereto, the electromagnets, braking-magnets, the bearing-pieces of the armature-axle being mounted side by side on said bearing-bolts, distance-pieces interposed between said parts, means to secure said parts in position, the cover of the meter-casing mounted on said bearing-bolts and means to secure it thereon, substantially as and for the purpose specified.

35 19. In an electric meter of the class described, a base-plate, bearing-bolts suitably secured thereto, the electromagnets, braking-magnets and the bearing-pieces of the armature-axle being mounted side by side on said bearing-bolts, distance-pieces interposed between said parts, tie-pieces to insure the relative position of said bearing-bolts, means to secure the parts arranged on said bearing-bolts, the cover of the meter-casing mounted equally on the bearing-bolts and means to secure it thereon, substantially as and for the purpose specified.

40 20. In an electric meter of the class described, a base-plate, bearing-bolts suitably secured thereto, the electromagnets, permanent magnets, the bearing-pieces of the armature-axle and the registering mechanism being mounted side by side on said bearing-bolts, means to secure said parts in position, the cover of the meter-casing mounted equally on said bearing-bolts and means to secure it thereon, substantially as and for the purpose specified.

45 21. In an electric meter of the class described, a base-plate, bearing-bolts suitably secured thereto, the electromagnets, braking-magnets, the bearing-pieces of the armature-axle and the registering mechanism being mounted side by side on said bearing-bolts, distance-pieces interposed between said parts, means to secure said parts in position, the cover of the meter-casing being equally mounted on said bearing-bolts and means to secure it thereon, substantially as and for the purpose specified.

50 22. In an electric meter of the class described, a base-plate, bearing-bolts suitably secured thereto, the electromagnets, braking-magnets, the bearing-pieces of the armature-axle and the registering mechanism being mounted side by side on said bearing-bolts, distance-pieces interposed between said parts, means to secure said parts in position, tie-pieces insuring the relative position of said bearing-bolts, the cover of the meter-casing mounted equally on said bearing-bolts and means to secure it thereon, substantially as and for the purpose specified.

55 In witness whereof I have hereunto set my hand in presence of two witnesses.

OTTO TITUS BLÁTHY.
